RAILWAY TRAFFIC CONTROLLING APPARATUS

James J. Van Horn, Pittsburgh, Pa., assignor to
The Union Switch & Signal Company, Swiss-
vale, Pa., a corporation of Pennsylvania

Application September 16, 1941, Serial No. 410,987

14 Claims. (Cl. 246—3)

My invention relates to railway traffic controlling apparatus and more specifically, to the control of traffic in a stretch of single track, two-direction railway wherein centralized traffic control or some other suitable form of manual control is employed in establishing the direction. Some of the distinguishing features of my system are that it is of the normally deenergized track circuit type, employs neutral track circuits, and dispenses with all control line wires except for the C. T. C. coded line circuit, if C. T. C. is used. The present invention is an improvement on the inventions disclosed in my copending applications Serial Nos. 410,504 and 410,717 filed on September 12, 1941, and September 13, 1941, respectively, for Railway traffic controlling apparatus, the former of which became Patent No. 2,344,573 dated March 21, 1944.

One object of my invention is to provide a normally deenergized track circuit system of signaling which employs non-polarized or neutral track circuits for controlling traffic moving in either direction on a single track and which employs no control line wires for the usual signaling functions. Another object of my invention is to provide means for retaining the established traffic direction as long as a train is approaching or occupying the single track stretch, solely by means of the track circuit apparatus, without depending on any circuits or apparatus located at the C. T. C. office. Other objects, purposes and characteristic features of my invention will be apparent from the description which follows.

I accomplish the foregoing objects as follows: I transmit a C. T. C. code to the new exit end of the single track stretch which causes a normal or master track circuit code to be applied at the exit end for setting up traffic in the desired direction over the stretch. This normal track circuit code is cascaded over the track circuits to the new entrance end where it initiates the supply of a reverse or feed back code during off intervals of the master code. The feed back code is cascaded back to the exit end and when there received indicates that the entrance signal is at stop and that the stretch of track is unoccupied. The absence of this feed back code at the exit end is used to prevent cutting off of the master code for the purpose of retaining the new traffic direction as long as a train is approaching or occupying the single track stretch. I make no distinction as to the relative polarity of the master and feed back codes, these codes being either of the same or of opposite polarity. I depend, instead, on the order in which these codes are

received at a signal location or other point of the track circuit for determining proper response of the direction establishing and direction maintaining apparatus. Code is retained on the track circuits ahead of the train through the absence of the feed back code so that no intercontrols need be provided on the C. T. C. machine for retaining a route which has been established and for preventing conflicting routes from being established.

I shall describe one form of apparatus embodying my invention and shall then point out the novel features thereof in claims.

Figs. 1a and 1b of the accompanying drawings when placed end to end with Fig. 1a at the left, are a diagrammatic view showing one form of apparatus embodying my invention.

Similar reference characters refer to similar parts in each of the two figures.

20 Referring to the drawings, the stretch of single track between the two passing sidings PS₁ and PS₂ is divided into track circuit sections by means of the usual insulated rail joints at locations D, E, F, and G. E is a cut section location and F is an intermediate signal location. Extending from one end of the single track stretch to the other is a C. T. C. control line over the two wires of which control codes originating in the C. T. C. machine at the control point or office can be transmitted to the one or the other of the two field stations corresponding with the two ends of the stretch, for setting up traffic in one or the other direction. Indication codes can likewise be received at the office over the C. T. C. line from these stations or from suitable intermediate points. Since the C. T. C. apparatus, of itself, forms no part of my present invention, it will be sufficient for an understanding of my system to point out that when the traffic lever 8 (which forms a part of the C. T. C. machine) is moved to its right-hand or R position, the eastbound traffic relay 8RFSR will be picked up (due to the transmission of a control code over the line), whereas when this lever is moved to the left-hand or L position, the westbound traffic relay 8LFSR will be picked up. Normally, this lever will occupy its neutral or N position in which neither traffic relay is energized, the head-block signals are at stop, and the track circuits of the single track stretch are deenergized. One form of C. T. C. control and indication apparatus which may conveniently be used with apparatus embodying my invention is that shown in

L. V. Lewis on January 21, 1941, for Remote control system.

As shown in the drawings, all of the apparatus (except the approach track circuits 5T and 9T at the two ends) is deenergized since traffic lever 8 occupies its N position. If the operator now wishes to establish traffic in the westbound direction, he will move lever 8 to its L position so as to send out a code which will energize the traffic direction relay 8LFSR at the field station which is associated with location D. The pick-up of relay 8LFSR causes relay 6RTCTM to follow 75 or 180 code depending on the position of contact 11 of the home relay 6LAH for signal 6L. If the signal is at clear or caution, relay 6LAH will be energized so that the front point of contact 11 will apply 180 code to relay 6RTCTM. If the signal is at stop, however, as shown, then the back point of contact 11 will be closed and 75 code will be supplied to relay 6RTCTM. The coding operation of relay 6RTCTM will apply 75 code from the track battery TB to the track section 6RT over a circuit which includes the front point of contact 12 of relay 6RTCTM, and front contacts 13 and 14 of relays 6RK and 5TR. Relay 6RK repeats the deenergized position of signals 6RA and 6RB, and is energized when and only when these signals are at stop, thus providing a check on the stop position of these signals before code can be applied to the stretch for a westbound move. The functions and control of relays 6LAH and 6RK are well known and it is deemed sufficient to indicate the control of these relays from signals 6L and 6RA and 6RB, respectively, by means of the broken line connections which join these relays with the signals. The inclusion of front contact 14 of relay 5TR in the code feed circuit is for the purpose of insuring that no train is occupying the approach section 5T.

The 75 code which is supplied to section 6TR is detected at location E by the code following track relay 6WTR which energizes the decoding transformer DT and causes pick-up of the 75 and 180 code decoding relay 6WHR over the rectifying contact 15 of relay 6WTR and the back point of contact 16 of relay 6EHR. The track relay 6WTR as well as all of the remaining track relays associated with the single track stretch may be of the neutral or non-polarized type since no dependence is placed upon the polarity of the track circuit current. Of course, it is obvious that biased polar two-position relays may also be used, and a certain amount of additional foreign current protection will result from such use. However, such polar relays are not at all necessary from the standpoint of operativeness of my system. Relay 6EHR will be deenergized under the assumed condition, as will relay 6EFB. Accordingly, relay 6ECTM will now be energized and will follow 75 code over a circuit which includes the coding contact 17 of relay 6WTR, front contact 18 of relay 6WHR, and the back points of contacts 19 and 20 of relay 6EFB. Relay 6ECTM will repeat the 75 code into the cut section 6ART over the front point of its contact 21. The 75 code in section 6ART is decoded by track relay 7WTR at location F which results in the energization of relay 7WHR in substantially the same manner as at location E. The circuit for relay 7WHR includes the rectifying contact 22 of relay 7WTR, and the back points of contacts 23 and 24 of relay 7EHR and of the eastbound directional stick relay ESR, respectively.

The track section 10LT will now receive 180 code by virtue of the energization of code following relay 7ECTM on 180 code over a circuit which includes the code terminal 180B which supplies 180 code, front point of contact 44 of relay 7WHR, and the back points of contacts 26 and 27 of relay 7EFB. Relay 10LTR at location G will follow this code, energizing the decoding transformer DT and thus causing the code detecting relay 8LFR to pick up over a circuit which includes the rectifying contact 28 of relay 10LTR and the back point of contact 29 of the eastbound traffic direction relay 8RFSR. Relay 8RFSR will, of course, be deenergized at all times except when lever 8 is moved to its R position and conditions are then proper for establishing eastbound traffic over the stretch.

With relay 10LTR following code and relay 8RFSR deenergized, an impulse circuit is provided for causing relay 10LTCTM to follow code also, and thus to apply impulses of a 180 feed back code to section 10LT during the off intervals of the master code being received by relay 10LTR. The manner in which the feed back code is supplied to the section during off intervals in the master code is well known and is described in the United States Reissue Patent No. 21,783 granted to Herman G. Blosser on April 29, 1941, so that this description need not be repeated. The impulse circuit for relay 10LTCTM includes the front contact 30 of relay 8LFR. The feed back code circuit will be established only if signals 10LA and 10LB are at stop (front contact 31 of relay 10LKM closed) and if section 9T is unoccupied (front contact 32 of relay 9TR closed).

The feed back code is now detected at location F by relay 7ETR, and since relay 7WHR is picked up due to energization on master code, relay 10TWFB will be picked up over a circuit which includes the rectifying contact 33 of relay 7ETR, wire 34, front point of contact 35 of relay 7WHR, and wires 36 and 37. Relay 7WFB, when picked up, closes an obvious energizing circuit for relay 7WCTM from transformer DT so that feed back code (which is 75 code in this cut section) is supplied to the section 6ART during the off intervals of the 75 master code to which relay 7WTR is now responding.

The feed back code in section 6ART is detected at location E by relay 6ETR which causes relay 6WFB to pick up and to close the impulse coding circuit for relay 6WCTM, as at location F. Relay 6WCTM applies feed back code to section 6RT for operating relay 6RTR at location D to thereby energize relay WFB. This relay will become energized because the front point of contact 38 of relay 8LFSR remains closed, due to lever 8 having been moved to the L position. The pick-up of relay WFB indicates that the single track stretch is unoccupied and that signal 10L is at stop since master code has been cascaded to the entrance end and feed back code has been cascaded from the entrance end to the exit end. Relay WFB controls the transmission of a suitable indication code to the office and also enters into the control of relay 8LFSR by closing a stick circuit for the latter relay over its back contact 48 and the front contact 49 of relay 8LFSR. Accordingly, once relay WFB is released due either to the clearing of signal 10L or occupancy of the stretch, relay 8LFSR is retained energized so that the traffic direction cannot be changed. Once the block indication transmitted by relay WFB is received at the office, the operator may

send out a suitable code to clear the entrance signal 10LA or 10LB. These signals can be cleared only if master code has been received at the entrance end G, as indicated by the prior energization of relay 8LFR at this location. A westbound train may now be permitted to pass signal 10L and enter the single track stretch.

The block indication circuits, control of relay 8LFSR by relay WFB (or control of relay 8RFSR by relay EFB), and control of electric switch locks, shown and claimed in my copending application Serial No. 410,717 referred to hereinbefore, may be readily incorporated into the system embodying my present invention to extend the application thereof, but these added complications have not been shown in order to simplify the disclosure as much as possible.

Referring to contact 39 of relay 8RFR at location D, the inclusion of this contact in the circuit of relay 6RTCTM, in addition to establishing the feed back code circuit for eastbound traffic, prevents the possibility of certain undesired cyclic action occurring in the apparatus when relay 8LFSR is deenergized, following movement of lever 8 to the R position for a reversal of traffic from westbound to eastbound. Contact 30 of relay 8LFR (location G) is similarly included in the circuit for relay 10LTCTM to prevent the cyclic action occurring following a traffic reversal from eastbound to westbound, as well as to establish the westbound feed back code circuit.

With traffic established in the westbound direction, when a train passes signal 10L and enters section 10LT, relay 10LTR will be shunted so that relay 10LTCTM will cease operating and will discontinue the supply of feed back code to section 10LT. Relay 7ETR at location F will accordingly cease operating and will discontinue the energization of relay 7WFB so that relay 7WCTM will also cease operating. Accordingly, feed back code will be removed from sections 6ART and 6RT, causing relay 6RTR at location D to release and to deenergize relay WFB thus providing a "block occupied" indication. Master code will, however, continue to be supplied in the eastbound direction toward the train because relay 6RTCTM will continue its coding action since relay 8LFSR remains energized until the traffic movement is completed and the operator restores or reverses the lever 8.

Returning to the intermediate signal location F, as the westbound train passes this location, the westbound directional stick relay WSR will become energized. The pick-up circuit for this relay includes the front contact 40 of the westbound approach relay WAR (which picks up when the train approaches within a certain distance of location F, in the usual manner), and the front point of contact 41 of relay 7WHR (already deenergized but not yet released because of its slow acting characteristic). When relay WSR picks up, it closes a stick circuit for itself over its front contact 42 and the back point of contact 41 of relay 7WHR. Relay WSR will remain picked up during the time that the train occupies any part of the block D-F since relay 7WHR will remain deenergized during this whole time. Relay WSR will apply 75 code for operating relay 7ECTM, over its front contact 43 and the back point of contact 44 of relay 7WHR. Accordingly, as soon as the train vacates section 10LT, 75 code supplied over the front point of contact 45 of relay 7ECTM will be effective in the rear section for permitting a following westbound train to enter the stretch.

When the train clears section 6RT (and 5T), relay 7WHR will pick up, releasing the westbound stick relay WSR in the usual manner and transferring the coding circuit for relay 7ECTM to the front point of contact 44 of relay 7WHR. The code fed to section 10LT will now be 180, since the block ahead is clear. Exit of the westbound train from the stretch will cause receipt of the feed back code by relay 6RTR, as before, and re-energization of relay WFB. The operator may now either leave the lever 8 in its L position to permit additional westbound traffic to pass over the stretch, or he may place the lever in its N position so as to remove energy from the track circuits.

When establishing traffic in the eastbound direction, the operator will move lever 8 to the R position in order to transmit a code which will cause pick-up of the eastbound traffic direction relay 8RFSR so as to initiate the supply of master code in the westbound direction from location G to location D. The sequence of operations taking place in setting up the eastbound traffic direction is identical with that described in detail above for the westbound move and will be understood without further explanation.

It will be noted that in my system, the HR relays for the two directions at an intermediate location or cut section are so inter-controlled that only the westbound HR relay (or only the eastbound HR relay) and its corresponding FB relay can be energized at any one time. The master code picks up either the westbound or the eastbound HR relay, depending upon the traffic direction being established at the time.

When the master code gets through to the entrance end and feed back code returns, the feed back code then picks up the corresponding FB relay (WFB if traffic is to be westbound; EFB if traffic is to be eastbound). Accordingly, each track circuit junction within the single track stretch in my system has associated therewith an eastbound and a westbound track relay and an eastbound and a westbound code transmitting relay. The system being normally deenergized, the track relays at a given junction will pick up in a predetermined order, depending upon the direction from which the master code reaches the junction. If the master code is cascaded in the westbound direction, then the eastbound track relay will be first to pick up and will lock out the westbound track relay at that location from being operated on master code, thus causing eastbound traffic conditions to be established at that location. The westbound track relay will respond only to feed back code under the assumed condition. In this manner, the system insures satisfactory traffic direction selection and proper maintenance of the direction when once established. It will be apparent also that I provide a pair of track circuits, an eastbound and a westbound one, over the same rails between each pair of consecutive junctions referred to above. Application of master code at one end of the stretch causes one track circuit of each such track circuit pair to respond only to master code and the other track circuit of each pair to respond only to feed back code. When master code is applied to the other end of the stretch, the response of these track circuits to the two codes is automatically reversed.

Under certain conditions, some difficulty may be experienced in obtaining fully satisfactory response of certain track relays to the feed back code. It will be understood that an impulse of feed back code must be supplied during an off in-

terval in the master code and under certain conditions the time characteristics of the apparatus may be such that the feed back impulse is of relatively short duration. To insure that the track relays will respond properly even to very short feed back impulses, these relays can be provided with an auxiliary stick winding energized over a front contact of the associated FB relay and a front contact of the track relay itself. This manner of improving the operation of a relay on feed back code is shown and described in United States Patent No 2,172,893 granted to E. U. Thomas on September 12, 1939, so that details of this operation need not be repeated here.

It will be apparent that the system embodying my invention will operate properly when the intermediate locations E and F are eliminated and the stretch D—G includes but one track circuit section. This section will include the track circuit pair described above and the track circuits of the pair will be selectively effective for master code or for feed back code, according as the master code is applied at one or the other end of the stretch, as pointed out above.

From the foregoing, it will be apparent that I have provided a normally deenergized coded track circuit system of signaling for traffic moving in either direction on a stretch of single track, in which a master track circuit code provides controls for the signals such that these will display aspects in conformity with the block conditions, and a feed back code which checks that the stretch is unoccupied and that the entrance signals are at stop. A reversal of the traffic direction is permitted only if the stretch is unoccupied and the entrance signals are at stop, the established traffic direction being retained during occupancy and during the time that the entrance signal is cleared. The master and feed back codes may be of either polarity, and neutral track circuits may be used. The selective response of the westbound or eastbound HR (code detecting) relay at a given location to master code depends on whether the traffic direction being established is westbound or eastbound. If the traffic direction is westbound, then relay WHR will respond to the master code and relay WFB will respond to feed back code. If the traffic direction is eastbound, the same thing will be true for relays EHR and EFB. Accordingly, polarized track circuits are not required in my system, and master code is retained on the track ahead of a train through the absence of the feed back code rather than by means of inter-controls on the C. T. C. machine.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination with a stretch of track over which traffic may move in either direction, said stretch being divided into a plurality of track circuit sections, a traffic direction control relay adjacent the exit end of said stretch for a given direction of traffic movement, manually controlled means for operating said control relay, a stick circuit for said control relay effective when said relay is operated, means effective when said control relay is operated for cascading track circuit current impulses of a master code of a given relative polarity from said exit end over said sections to the entrance end of the

stretch for checking unoccupancy, whereby if said stretch is occupied said master code will be shunted out and so will not reach said entrance end, traffic governing means operated in response to the receipt of master code at said entrance end, a signal for governing the entry of traffic moving in said given direction into said stretch, means controlled by said traffic governing means when operated effective if said signal is at stop for cascading track circuit current impulses of a feed back code of the same relative polarity from said entrance end over said sections to said exit end during off intervals in said master code, and means responsive to the receipt of feed back code at said exit end for rendering said stick circuit ineffective, whereby if said signal is cleared and a train occupies said stretch so that said feed back code is shunted and is not received at said exit end said stick circuit will cause said given traffic direction to be retained.

2. In combination with a stretch of track over which traffic may move in either direction, said stretch being divided into a plurality of track circuit sections, a traffic direction control relay adjacent the exit end of said stretch for a given direction of traffic movement, manually controlled means for operating said control relay, a stick circuit for said control relay effective when said relay is operated, means effective when said control relay is operated for cascading track circuit current impulses of a master code of a given relative polarity from said exit end over said sections to the entrance end of the stretch for checking unoccupancy, whereby if said stretch is occupied said master code will be shunted out and so will not reach said entrance end, a signal for governing the entry of traffic moving in said given direction into said stretch, means effective when and only when said master code is received at said entrance end and said signal is at stop for cascading rail current impulses of a feed back code of the same relative polarity from said entrance end over said sections to said exit end during off intervals in said master code, and means responsive to the receipt of feed back code at said exit end for rendering said stick circuit ineffective, whereby if said signal is cleared and a train occupies said stretch so that said feed back code is shunted and is not received at said exit end said stick circuit will cause said given traffic direction to be retained.

3. In combination with a stretch of track over which traffic may move in either direction, said stretch being divided into a plurality of track circuit sections, manually controlled means for supplying track circuit current impulses of a master code to the rails at the exit end of said stretch for a given direction of traffic movement, means including neutral track relays for cascading said master code from said exit end over said sections to the entrance end of the stretch for checking unoccupancy, whereby if said stretch is occupied said master code will be shunted out and so will not reach said entrance end, traffic governing means operated in response to the receipt of master code at said entrance end, a signal for governing the entry of traffic moving in said given direction into said stretch, means controlled by said traffic governing means when operated effective if said signal is at stop for cascading rail current impulses of a feed back code during off intervals in said master code from said entrance end over said

sections to said exit end, and means responsive to the receipt of feed back code at said exit end for governing said manually controlled means, whereby if said signal is cleared and a train occupies said stretch said feed back code will be shunted and will not be received at said exit end.

4. In combination with a stretch of track over which traffic may move in either direction, said stretch being divided into a plurality of track circuit sections, manually controlled means for supplying track circuit current impulses of a master code to the rails at the exit end of said stretch for westbound traffic, means including a neutral westbound track relay for each of said sections for cascading said master code from said exit end over said sections to the entrance end of the stretch for checking unoccupancy, whereby if said stretch is occupied said master code will be shunted out and so will not reach said entrance end, traffic governing means operated in response to the receipt of master code at said entrance end, a signal for governing the entry of westbound traffic into said stretch, means controlled by said traffic governing means when operated effective if said signal is at stop for supplying track circuit current impulses of a feed back code during off intervals in said master code to the rails at said entrance end, means including a neutral eastbound track relay for each of said sections for cascading said feed back code from said entrance end over said sections to said exit end, and means responsive to the receipt of feed back code at said exit end for governing said manually controlled means, whereby if said signal is cleared and a train occupies said stretch said feed back code will be shunted and will not be received at said exit end.

5. In combination with a stretch of track over which traffic may move in either direction, said stretch being divided into track circuit sections, an eastbound and a westbound entrance signal for said stretch, an eastbound and a westbound track relay for each of said sections, said track relays being neutral with respect to polarity, a westbound traffic direction selector adjacent the westbound exit end of said stretch, an eastbound traffic direction selector adjacent the westbound entrance end of said stretch, means effective when said westbound selector is operated and including said westbound track relays for cascading track circuit current impulses of a master code from said westbound exit end over said sections to said westbound entrance end, whereby if said stretch is occupied said master code will be shunted out and will not reach said entrance end, means including said eastbound track relays effective when said master code is received at said entrance end and said westbound signal is at stop for cascading track circuit current impulses of a feed back code during off intervals in said master code from said entrance end over said sections to said exit end, means effective when said eastbound selector is operated during unoccupancy of said stretch and including said eastbound track relays for cascading track circuit current impulses of said master code from said westbound entrance end over said sections to said westbound exit end, means including said westbound track relays effective when said master code is received at said westbound exit end and said eastbound signal is at stop for cascading track circuit current impulses of a feed back code during off intervals in said master code

from said exit end over said sections to said entrance end, whereby if either of said signals is cleared and a train occupies said stretch said feed back code will be shunted out, and means at each end of the stretch responsive to the receipt of said feed back code at that end for controlling the associated traffic direction selector.

6. In combination with a stretch of track over which traffic may move in either direction, an eastbound and a westbound track circuit for said stretch each including the same track rails, a westbound neutral track relay adjacent one end of said track circuit and a westbound source of rail current adjacent the other end, an eastbound neutral track relay adjacent said other end and an eastbound source of rail current adjacent said one end, manually controlled means for supplying rail current impulses of a master code from said westbound source to operate said westbound track relay and so to check unoccupancy, whereby if said track circuit is occupied said master code will be shunted out, a westbound entrance signal for said stretch, means controlled by said westbound track relay when operating on said master code, effective if said westbound signal is at stop for supplying rail current impulses of a feed back code from said eastbound source during off intervals in said master code to thereby operate said eastbound track relay, whereby if said signal is cleared for a westbound train which enters said stretch and shunts said feed back code said eastbound track relay will not be operated, and means responsive to operation of said eastbound track relay on said feed back code for governing said manually controlled means.

7. In combination with a stretch of track over which traffic may move in either direction, an eastbound and a westbound track circuit for said stretch each including the same track rails, a westbound neutral track relay adjacent one end of said track circuit and a westbound source of rail current adjacent the other end, an eastbound neutral track relay adjacent said other end and an eastbound source of rail current adjacent said one end, manually controlled means for selectively supplying rail current impulses of a master code from one said source or the other in accordance with the traffic direction being established to thereby operate the associated track relay on said master code and so to check unoccupancy, whereby if said track circuit is occupied said master code will be shunted out, an entrance signal for each end of the stretch, means controlled by said track relay when operating on said master code effective if the associated entrance signal is at stop for supplying rail current impulses of a feed back code from the remaining one of said two sources during off intervals in said master code to thereby operate the remaining one of said track relays, whereby if said associated signal is cleared for a train which enters said stretch and shunts said feed back code said last-named relay will not be operated, and means responsive to operation of said last-named relay on said feed back code for governing said manually controlled means.

8. In combination with a normally deenergized stretch of track over which traffic may move in either direction, an eastbound and westbound track circuit for said stretch each including the same track rails, a normally connected westbound neutral track relay adjacent one end of said track circuit and a normally disconnected westbound source of rail current adjacent the

other end, a normally connected eastbound neutral track relay adjacent said other end and a normally disconnected eastbound source of rail current adjacent said one end, manually controlled means for periodically connecting said westbound source across the rails so as to supply rail current impulses of a master code to operate said westbound track relay and so to check unoccupancy, whereby if said track circuit is occupied said master code will be shunted out, a westbound entrance signal for said stretch, means controlled by said westbound track relay when operated effective if said signal is at stop for periodically connecting said eastbound source across the rails during off intervals in said master code so as to supply rail current impulses of a feed back code during off intervals in said master code to thereby operate said eastbound track relay, whereby if said signal is cleared for a westbound train which enters said stretch and shunts said feed back code said eastbound track relay will not be operated, and means responsive to operation of said eastbound track relay on said feed back code for governing said manually controlled means.

9. In combination with a stretch of track over which traffic may move in either direction, a first and a second track circuit for said stretch each including the same track rails, a first neutral track relay adjacent one end of said track circuit and a first source of rail current adjacent the other end, a second neutral track relay adjacent said other end and a second source of rail current adjacent said one end, manually controlled traffic direction means effective when operated for supplying rail current impulses of a master code from said first source to operate said first track relay and so to check unoccupancy, whereby if said track circuit is occupied said master code will be shunted out, an entrance signal for each end of the stretch, means controlled by said first track relay when operated effective if the associated entrance signal is at stop for supplying rail current impulses of a feed back code from said second source during off intervals in said master code to thereby operate said second track relay, whereby if said associated signal is cleared for a train which enters said stretch and shunts said feed back code said second track relay will not be operated, and means responsive to operation of said second track relay on said feed back code for governing said manually controlled means.

10. In combination with a stretch of railway track over which traffic may move in either direction, a first and a second track circuit for said stretch each including the same track rails, a first neutral track relay adjacent one end of said track circuit and a first source of rail current adjacent the other end, a second neutral track relay adjacent said other end and a second source of rail current adjacent said one end, a first traffic direction relay effective when operated for supplying rail current impulses of a master code from said first source to operate said first track relay, a second traffic direction relay effective when operated for supplying rail current impulses of the master code from said second source to operate said second track relay, means effective for selectively operating said first or said second traffic direction relay to thereby check unoccupancy, whereby if either track circuit is occupied said master code will be shunted out, an entrance signal for each end of the stretch, means effective when either of said

track relays is operating on said master code effective if the associated entrance signal is at stop for supplying rail current impulses of a feed back code during off intervals of the master code from the source of rail current which is associated with the other of said track relays for operating said other track relay, whereby if said associated signal is cleared for a train which enters said stretch and shunts said feed back code said other track relay will not be operated, and means responsive to operation of said other track relay on said feed back code for governing the associated traffic direction relay.

11. In combination with a normally deenergized stretch of railway track over which traffic may move in either direction, a track circuit junction within said stretch defining the ends of a first and a second adjoining track section, a westbound track relay for said first section adjacent said junction, an eastbound track relay for said second section also adjacent said junction, westbound and eastbound traffic direction control means, means for selectively operating said westbound or said eastbound traffic direction means, means controlled by said traffic direction means for supplying rail current impulses of a master code first to said first section and then to said second section or first to said second section and then to said first section according as said westbound or said eastbound means is operated respectively, said master code operating said westbound or said eastbound track relay respectively to check unoccupancy, whereby if either of said sections is occupied said master code will be shunted away from the track relay associated therewith, an entrance signal for each end of the stretch, means controlled by one of said track relays which is first operated on master code effective if the associated entrance signal is at stop for causing rail current impulses of a feed back code to be supplied to the other section during off intervals in the master code for operating the track relay associated with said other section, whereby if said associated signal is cleared for a train which enters said stretch and shunts said feed back code said last-named track relay will not be operated, and means controlled by said last-named track relay for governing the associated traffic direction control means.

12. In combination with a normally deenergized stretch of railway track over which traffic may move in either direction, a track circuit junction within said stretch defining the ends of a first and a second adjoining track section, a westbound track relay for said first section adjacent said junction, an eastbound track relay for said second section also adjacent said junction, traffic direction control means for causing rail current impulses of a master code to be supplied first to said first section or first to said section to thereby operate said westbound or said eastbound track relay respectively to check unoccupancy, whereby if either of said sections is occupied said master code will be shunted away from the track relay associated therewith, means controlled by the first of said two track relays which is operated on master code for preventing operation of the remaining track relay on master code until the order in which said sections receive said master code is reversed by said traffic direction control means, an entrance signal for each end of the stretch, means controlled by said first track relay effective if the associated entrance signal is at stop for supplying rail current im-

pulses of a feed back code during off intervals in said master code to thereby operate said remaining track relay, whereby if said associated signal is cleared for a train which enters said stretch and shunts said feed back code said remaining track relay will not be operated, and means controlled by said remaining track relay for governing said traffic direction control means.

13. In a normally deenergized coded track circuit signaling system, in combination, adjacent first and second track sections through which traffic may move in either direction, means for at times supplying master code energy and at other times for supplying feed-back energy to the rails of the first section at the end thereof remote from the second section, means for at times supplying master code energy and at other times supplying feed-back energy to the rails of the second section at the end thereof remote from the first section, a code following track relay for each of said sections at the end thereof adjacent the other section and operated by either master code or feedback energy supplied over the rails of the section with which the relay is associated, each of said track relays having associated therewith normally deenergized electroresponsive means which becomes energized upon operation of the track relay when and only when the electroresponsive means associated with the other track relay is deenergized and which when energized remains energized during subsequent code following operation of the track relay and also during occupation of the associated track section by a train leaving the other section, means for each of said sections for supplying master code energy to the section rails at the end of the section adjacent the other section when and only when the electroresponsive means associated with the track relay for the other section is energized, and means responsive to operation of each of said track relays when the electroresponsive means associated with the other track relay is energized.

14. In a normally deenergized coded track circuit signaling system, in combination, adjacent first and second track sections through which traffic may move in either direction, means for at times supplying master code energy and at other times for supplying feed-back energy to the rails of the first section at the end thereof remote from the second section, means for at times supplying master code energy and at other times supplying feed-back energy to the rails of the second section at the end thereof remote from the first section, a code following track relay for each of said sections at the end thereof adjacent the other section and operated by either master code or feed-back energy supplied over the rails of the section with which the relay is associated, each of said track relays having associated therewith normally deenergized electroresponsive means which becomes energized upon operation of the track relay when and only when the electroresponsive means associated with the other track relay is deenergized and which when energized remains energized during subsequent code following operation of the track relay and also during occupation of the associated track section by a train leaving the other section, means for each of said sections for supplying master code energy to the section rails at the end of the section adjacent the other section when and only when the electroresponsive means associated with the track relay for the other section is energized, means for each of said sections responsive to operation of the track relay for the section for supplying feed-back energy to the section rails at the end of the section adjacent the other section when and only when the electroresponsive means associated with the said track relay is energized, and means responsive to operation of each of said track relays when the electroresponsive means associated with the other track relay is energized.

JAMES J. VAN HORN.
